UNITED STATES PATENT OFFICE.

THEODORE C. KREMER, OF SHARPSBURG BOROUGH, PENNSYLVANIA, ASSIGNOR TO
LIGHTNING COUPLER LINK COMPANY, OF SHARPSBURG, PENNSYLVANIA, A
CORPORATION OF PENNSYLVANIA.

MULTIPLE COUPLING.

1,348,811.

Specification of Letters Patent.

Patented Aug. 3, 1920.

Application filed April 18, 1919. Serial No. 290,924.

To all whom it may concern:

Be it known that I, THEODORE C. KREMER, a citizen of the United States, and residing in Sharpsburg borough, in the county of Allegheny and State of Pennsylvania, have invented or discovered new and useful Improvements in Multiple Couplings, of which the following is a specification.

My invention consists in a new and improved adjustable coupler for chains and for similar purposes.

In the use of the ordinary single or double coupler of the coacting hook type no means are provided for obtaining different degrees of tautness in the coupled chain or cable nor for taking up slack.

The object I have in view is the remedy of this defect.

Generally speaking, my improved coupler is of the coacting hook type and comprises a pair of plates pivotally connected together and provided with a plurality of pairs of oppositely disposed and coacting hooks. I also provide projecting ears on the ends 25 of the plates which may be conveniently grasped by the fingers in opening the coupler to release or receive a chain link or cable ring.

Novel features of construction and arrangement of parts will appear from the following description.

In the accompanying drawings, Figure 1 is a side view showing my invention applied to a coacting hook coupler, the same being shown closed and connecting together two chain ends; Fig. 2 is an edge view of the same; Fig. 3 is a side view showing the coupler open so that the chain end shown in dotted lines may be released; Fig. 4 is an elevation showing my invention applied to a double ended coupler, the same being shown open, and Fig. 5 is an elevation showing the same closed.

The following is a detailed description of the drawing, reference being first had to Figs. 1, 2 and 3.

A and B represent a pair of plates, which in the lighter and smaller forms of my improved coupler may be stamped from plate or heavy sheet metal, but in the heavier forms of my coupler should be malleable castings or forgings. At one end said plates A and B are pivoted together face to face

by the rivet or other pivot member 1 by means of which the clevis or half link 2 which is engaged by the link C of one of the chain ends, may also be secured to the coupler. The two plates are provided with two or more pairs of oppositely extending hooks 3—3 and 4—4, the members of which pairs, when the plates are in registration, overlap and coact to form pockets, such as 5 and 6 in which the link D of the other chain end may be engaged. In Figs. 1 and 2, the link D is engaged by the hooks 3—3 and thus is secured in pocket 5, while in Fig. 3 the link D is shown engaged by one of the hooks 4, so that should the coupler be closed, the link would be secured in the pocket 6, thus giving more slack or greater combined chain length.

To facilitate the opening of the coupler I provide the free ends of the plates A and B with projecting ears 7 which, when the coupler is closed, as shown in Fig. 1, do not register, so as to be conveniently grasped with the fingers and spread apart to open the coupler without the use of a tool.

In Figs. 4 and 5, I show my invention applied to a double ended coupler wherein the two plates A' and B' are hinged together face to face at their centers by the rivet 1^a, the opposite ends of each plate being provided with a plurality of hooks, the hooks on one end being in reverse to the hooks on the other end and the coacting hooks on the two plates being opposed. In the use of this form of my improved coupler a very material tightening or loosening of the chain may be effected without impairing the security of the connection.

My coupler is possessed of a number of substantial advantages over those of the prior art. Thus when used to connect up the cross chains to the annuli of anti-skid chains for motor vehicles, or to connect the ends of the annulus chain together, the connection can be quickly made or released without the use of tools and the proper tautness or slack may be afforded without difficulty. This feature is also of great advantage in heavy service, as for instance cargo slings for dock use, the proper tautness or snugness being quickly obtained. The grasping ears also are very advantageous as they enable the coupler to be opened with the fingers instead of prying

the coupler open with a screw driver or stick as is now necessary.

What I desire to claim is:

1. A multiple coupler consisting of a pair of flat plates pivoted together face to face and adapted to be swung into and out of overlapping registration, each plate beyond its pivotal connection being provided with a plurality of hooks turned toward the pivot, 10 and the hooks on the one plate being opposite to the corresponding hooks on the other plate, whereby when said plates are in registration said hooks coact in pairs to form pockets, whereby varying degrees of tautness may be obtained, substantially as set forth.
2. A multiple coupler consisting of a pair of flat plates pivoted together face to face and adapted to be swung into and out of overlapping registration, each plate beyond its pivotal connection being provided with a plurality of hooks faced toward the pivot, the corresponding hooks on the plates being opposed to each other to form pairs whereby 25 when the plates are in registration the corresponding hooks overlap and form a plurality of pockets at varying distances from the pivot whereby different degrees of tautness may be obtained, substantially as set forth.
3. A coupler for chain ends and similar purposes comprising a pair of plates pivoted together face to face and adapted to be swung into and out of overlapping registration, said plates being provided with oppositely disposed hooks which overlap, when the plates are in registration, to secure a chain link, and projecting ears on the ends of said plates adapted to be grasped by the 35 fingers to force said plates to swing out 40

of registration, said ears being spaced apart when said plates are in registration.

4. A coupler for chain ends and similar purposes comprising a pair of plates pivoted together face to face and adapted to be 45 swung into and out of overlapping registration, said plates being provided with oppositely disposed hooks which overlap, when the plates are in registration, to secure a chain link, and means on the opposite sides 50 of the plates adapted to be grasped by the fingers to swing said plates out of registration.

5. A coupler consisting of a pair of flat plates pivoted together face to face and 55 adapted to be swung into and out of overlapping registration, each plate beyond its pivotal connection being provided with a plurality of open sided hooks and the hooks on one plate being oppositely disposed to 60 the corresponding hooks on the other plate whereby when the said plates are in registration said hooks coact in pairs to form inclosures of varying distances from the pivot for the purpose specified. 65

6. A double ended coupler consisting of a pair of flat plates centrally pivoted together face to face adapted to be swung into and out of overlapping registration, each plate to each side of its pivot being provided with a plurality of open sided hooks, the hooks on one plate being oppositely arranged to the corresponding hooks on the other plate whereby when said plates are in registration the hooks coact in pairs to form 70 inclosures of varying distances from the pivot for the purpose specified. 75

Signed at Pittsburgh, Pa., this 14th day of April, 1919.

THEODORE C. KREMER.
